BABY FOOD TRAY

Joan M. Hoch, 244 S. Norton,
Los Angeles, Calif. 90004

Filed Apr. 1, 1969, Ser. No. 16,537

Term of patent 14 years

Int. Cl. D7—99

U.S. Cl. D44—10

FIG. 1 is a front perspective view of a baby food tray showing my new design; and

FIG. 2 is a side elevational view thereof.

I claim:

The ornamental design for a baby food tray, substantially as shown.
